UNITED STATES PATENT OFFICE.

THOMAS KRILE, OF PISEK, NORTH DAKOTA.

POSTAGE-STAMP BOX.

1,285,240.

Specification of Letters Patent. Patented Nov. 19, 1918.

Application filed January 10, 1918. Serial No. 211,234.

To all whom it may concern:

Be it known that I, THOMAS KRILE, a citizen of the United States, residing at Pisek, in the county of Walsh, State of North Dakota, have invented certain new and useful Improvements in Postage-Stamp Boxes; and I do hereby declare the following to be a full, clear, and exact description of the invention, such as will enable others skilled 10 in the art to which it appertains to make and use the same.

The invention relates to a stamp box and more particularly to the class of postage stamp holders or receptacles for use by mail 15 carriers in rural districts.

The primary object of the invention is the provision of a holder or receptacle of this character wherein postage stamps of different denominations in strip form are 20 conveniently held therein so that the same can be fed singly therefrom with despatch and separated from the strips in the distribution thereof, the holder or receptacle being particularly adaptable for use by mail 25 carriers in rural districts for the convenient handling of the stamps, both in the carriage of the same and when disposing thereof in the sale of said stamps.

Another object of the invention is the 30 provision of a holder or receptacle of this character wherein the stamps will be retained in independent groups and in strip form in accordance with the denominations thereof and may be readily ejected from the holder or receptacle in their strip formation, either singly or in predetermined 35 numbers by the user of the holder or receptacle when making sales in the distribution of the stamps.

40 A further object of the invention is the provision of a holder or receptacle of this character wherein the construction thereof is novel in form to hold the strips of postage stamps assorted and to permit the easy feeding of the strips therefrom for ejecting the required number of stamps to be separated from the strip or strips in the use of the holder or receptacle.

45 A still further object of the invention is the provision of a holder or receptacle of this character, which is simple in construction, economical and inexpensive to manufacture and effective in carrying out the purposes for which it is designed.

50 With these and other objects in view the

invention consists in the features of construction, combination and arrangement of parts, as will be hereinafter fully described, illustrated in the accompanying drawing and pointed out in the claim hereunto appended.

60 In the accompanying drawing:

Figure 1 is a top plan view of the holder or receptacle constructed in accordance with the invention, showing one of the stamp 65 strips partly ejected therefrom,

Fig. 2 is a vertical longitudinal sectional view through the holder or receptacle,

Fig. 3 is a front end elevation,

Fig. 4 is a sectional view on the line 4—4 70 of Fig. 1,

Fig. 5 is a top plan view showing the cover or lid and a part of the top broken away.

Referring to the drawing in detail, A designates generally a box like body, preferably of rectangular shape open at its top for substantially one half of the length of the body, the remaining portion of the top of said body being closed through the medium of an extension 10 from the front end wall 11 of said body, which extension 10 is folded over onto the open top of the body A and is soldered or otherwise fastened to the sides 12 thereof. Formed interiorly of 85 the body A longitudinally thereof are spaced parallel upstanding partitions or division walls 13 providing independent compartments or chambers within the body, the free edge of the extension 10 being longitudinally slotted at the points of location of the partitions or division walls 13 and these slots 14 extending only a slight distance to provide therebetween tongues which are downwardly and upwardly 90 curved to form rounded guides 15 at the free edge of the extension 10 for the respective strips 16 of postage stamps of different denominations, the strips being folded into layers one upon the other within the 100 compartments or chambers interiorly of the body A are adapted to slide over the extension 10 which forms a bed therefor when ejecting the same from the holder or receptacle in a manner presently described.

105 The guides 15 provide at their adjacent end edges abutments for the partitions or division walls 13 to prevent any lateral displacement thereof and thus rigidly hold the same in their vertical position within 110

the body A, the partitions or walls 13 being soldered or otherwise fastened to the bottom and opposite ends of the body. These guides 15 avoid severing the stamp strips 16 when drawn taut on pulling the same outwardly from the body of the receptacle A as the extension 10 is devoid of any sharp edges at the free end thereof.

Bridging the extension 10 is a stationary 10 cover section or top section 17 which is formed with down turned opposite side edges forming flanges 18 which are soldered or otherwise fastened to the sides of the body A with the cover or top section 17 slightly 15 superposed relative to the extension 10 to provide a guide way or ejecting passage 19 therebetween for the strips of stamps 16 which are adapted to be fed through the guide way or passage 19 for ejecting the 20 stamps from the holder or receptacle.

Formed in the stationary cover or top section 17 in alinement with the paths of movement of the strips 16 of stamps through the guide way or passage 19 are 25 sight openings or windows 20 so that the stamps of the strips 16 are readily visible therethrough as each stamp in the strip is adapted to register with the sight opening or window and the outermost stamps of the 30 respective strips are adapted to normally underlie the sight openings or windows and the thumb or other finger of the hand of the user of the holder or receptacle can readily engage the exposed stamps through the 35 sight openings or windows 20 for the feeding of the strips 16 outwardly of the guide way or passage 19 so that the outer ends of the strips can be grasped for the pulling of the same outwardly the required distance 40 for permitting the tearing of a single or any number of stamps from the strip or strips fed from the holder or receptacle.

Fixed to the under face of the stationary cover or top section 17 are forwardly extending leaf springs or resilient fingers 21 which protrude slightly into the sight openings or windows 20 to frictionally engage

the strips 16 for holding the said strips flat upon the bed or extension 10 and to prevent the free feeding of the strips 16 through the guide way or passage 19 to avoid the accidental ejecting of the stamps from the holder or receptacle.

Hinged or otherwise swingingly connected to the stationary cover or top section 17 is a lid or cover 22 which is constructed to frictionally telescope upon the body A when closed to cover the open top portion of said body and on the opening of the lid or cover 22 access may be had to the interior of the body for the placing of stamp strips therein or their removal therefrom.

From the foregoing it is thought that the construction and manner of use of the stamp holder or receptacle will be clearly 65 understood and therefore more extended explanation has been omitted.

What is claimed is:—

A receptacle of the character described comprising a body open at its top and having one end wall extended over a portion of the open top and fixed to the sides of the body, a stationary top section bridging the extension of the end wall and forming a guideway therebetween to permit the passage of strips of stamps therethrough from the interior of the body, a lid swingingly connected to the stationary section and closing the open top of the body, friction means carried by the stationary section for engaging the strips to hold the same flat against the end extension within the guide way, vertical partitions arranged interiorly of the body longitudinally thereof to form independent compartments for the strips, and guides cut and bent from the free edge of the extension and abutting opposite sides of the partitions.

In testimony whereof, I affix my signature, in the presence of two witnesses.

THOMAS KRILE.
